UNITED STATES PATENT OFFICE.

JAMES CALDWELL STELFOX, OF WESTMINSTER, LONDON, ENGLAND, ASSIGNOR TO
ARTHUR GRAHAM GLASGOW, OF RICHMOND, VIRGINIA.

WATER-GAS APPARATUS.

1,072,370.

Specification of Letters Patent. Patented Sept. 2, 1913.

Application filed December 15, 1911. Serial No. 665,935.

To all whom it may concern:

Be it known that I, JAMES CALDWELL STELFOX, a subject of the King of Great Britain and Ireland, residing at Westminster, London, England, have invented Improvements Relating to Water-Gas Apparatus, of which the following is a specification.

The object of this invention is to prevent the opening of the blast valves of water gas apparatus if the pressure of the air in the blast main be below that of the gas in the generating apparatus or below some fixed relation to the latter, and thus to prevent the passage of gas into the blast main, and the consequent formation of an explosive mixture in this main or in the machinery room. With this object in view, the blast valve or valves of the apparatus is or are controlled by a locking device actuated by differences in the pressures in the generating apparatus and the blast main.

In one arrangement, the blast main at the inlet of the blast valve and the gas generating apparatus at the outlet of the blast valve are connected respectively to two chambers having in connection with them a movable device which is oppositely subjected to the pressure in the two chambers so that any excess pressure in either chamber over the other causes the device to move; preferably the adjacent walls of the two chambers are constituted by diaphragms, the two diaphragms being connected as by a bar, and the diaphragms may be proportioned so as to move with any desired difference between the blast and gas pressures. This movement causes the bar or some connected lever to move into a slot in the blast valve spindle (or its operating rod) in such manner that the latter cannot be raised when the diaphragms are at one end of the stroke, but is free when the diaphragms are at the other end.

Referring to the accompanying drawings, Figure 1 is a view of part of a water gas generating plant fitted with a blast valve the opening of which is controlled according to this invention and Figs. 2 and 3 are a sectional plan and an elevation respectively of one form of the valve locking device.

A is the spindle or operating rod of a blast valve and B its guide or standard of the usual type.

C is the chamber connected to the gas generating apparatus, with diaphragm D.

E is the second chamber connected to the blast main, with diaphragm F. The movement of these diaphragms and the connecting bar G actuates the lever H and causes it to enter a slot in the operating rod A when the pressure in chamber C is higher than that in chamber E or bears some fixed relation to it (according to the relative areas of the two diaphragms). The lever H lies close underneath some stop such as indicated by J which prevents the operating rod A being raised when the lever H is in the slot. The movement of the diaphragms from the chamber E toward the chamber C, when the pressure in the chamber C falls to the required extent carries the lever H clear of the rod A so that the latter is free to be raised.

What I claim is:—

1. The combination with a water gas generating apparatus, its air blast main and air blast valve of a movable device adapted in one position to effect the locking of said valve closed and in another position to leave it free to be operated, said device being oppositely subjected to the respective pressures in the generating apparatus and the blast main for the purpose set forth.

2. The combination with water gas generating apparatus, its air blast main and air blast valve of two chambers connected with the blast main and generating apparatus respectively, adjacent walls of said chambers being constituted by flexible diaphragms and locking mechanism actuated by said diaphragms in suchwise as to prevent or permit the opening of the air blast valve according to the relative pressures in the blast main and in the generating apparatus, substantially as described for the purpose specified.

3. The combination with water gas generating apparatus, its air blast main and air blast valve of two chambers connected with the blast main and generating apparatus respectively, adjacent walls of said chambers being constituted by flexible diaphragms of such relative sizes that they are balanced by any desired difference between the blast and gas pressures and locking mechanism actuated by said diaphragms in suchwise as to prevent or permit the opening of the air blast valve according to the relative pressures in the blast main and in the generating apparatus, substantially as described for the purpose specified.

4. The combination with water gas generating apparatus, its air blast main and air blast valve of two chambers connected with the blast main and generating apparatus respectively, adjacent walls of said chambers being constituted by flexible diaphragms, a slotted valve spindle, a lever adapted to engage in the slot of said spindle, a connection between said lever and said diaphragms whereby said lever is actuated by said diaphragms in suchwise as to prevent or permit

the opening of the air blast valve according to the relative pressures in the blast main and in the generating apparatus, substantially as described for the purpose specified. 15

Signed at London, England, this sixth day of December, 1911.

JAMES CALDWELL STELFOX.
